United States Patent Office

Des. 221,303
Patented July 27, 1971

221,303

PIANO

Winsor D. White, Jr., Blowing Rock, N.C., assignor to
D. H. Baldwin Company, Cincinnati, Ohio

Filed Feb. 24, 1970, Ser. No. 21,571

Term of patent 14 years

Int. Cl. D17—01

U.S. Cl. D56—9

FIG. 1

FIG. 2

FIG. 3

FIG. 1 is an angular perspective view of a piano embodying my new design.

FIG. 2 is a front elevational view thereof.

FIG. 3 is a side elevational view thereof.

The back of the piano (not shown) is conventional. The side not shown is the same as the side shown.

I claim:

The ornamental design for a piano, substantially as shown and described.
